UNITED STATES PATENT OFFICE.

GEORGE H. MELLON, OF PITTSBURGH, PENNSYLVANIA.

GLASS CASKET.

1,345,210.

Specification of Letters Patent. Patented June 29, 1920.

Original application filed September 11, 1917, Serial No. 190,838. Divided and this application filed January 23, 1918. Serial No. 213,347.

To all whom it may concern:

Be it known that I, GEORGE H. MELLON, a citizen of the United States, residing at Pittsburgh, in the county of Allegheny and 5 State of Pennsylvania, have invented new and useful Improvements in Glass Caskets, of which the following is a specification.

This invention is a division of my pending application Serial Number 190,838, 10 filed September 11th, 1917, relates to an improvement in glass caskets and has for its primary object to provide a hinge construction whereby the lid may be effectively hinged to the body and the lid capable of being detached from the body when the contents thereof is being viewed.

An object of the invention is to so construct and arrange the parts of the frame that the ornamentation of the casket will 20 be increased and in such a manner that the metal used can be reduced for allowing more of the interior construction of the casket to be visible through the glass body.

Besides the above my invention is distinguished in the use of frames so arranged 25 that the casket may be carried from place to place and the lid effectively hinged to the body but capable of being removed therefrom without disturbing the position 30 of the individual parts.

With these and other objects in view the invention will be better understood from the following detailed description taken in connection with the accompanying drawings 35 wherein:

Figure 1 is a side elevation of my improved form of casket.

Fig. 2 is a perspective view of the lid frame.

Fig. 3 is a detailed view of the hinge connection.

Fig. 4 is a perspective view of a portion of the hinge connection.

Fig. 5 is a vertical sectional view through 45 the hinge.

Fig. 6 is a view showing the carrying frame connected to the band of the hinge construction.

Fig. 7 is a detailed sectional view of a 50 portion of the casket showing the tongue and groove connection between the lid and body.

Again referring to the drawings, numerals 1 and 2 designate the body and lid of 55 the casket which are composed of glass

having a tongue and grooved connection 3 with each other as shown in Fig. 7. This tongue and grooved connection consists of a continuous tongue extending around the lid and engaging a continuous groove in 60 the body and as this is old in the construction of caskets a complete view in the drawing will be eliminated. The lid 2 has connected thereto a one piece frame 4 consisting of a longitudinal band 5 placed around the 65 lid and having lateral extending clips 6 of any suitable construction that may be easily bent over the top of the lid as clearly shown in Fig. 1 of the drawing. The binding action between the band 5 and the lid and the 70 extension of the clips over the lid effectively hold the lid frame against movement. One longitudinal edge of the band 5 is formed into a rib or bead 7 and arranged directly over this bead are openings 8 and 9. At 75 this point I wish to call attention to the fact that this frame may be formed of one piece and welded at any suitable point such as at one corner of the frame as indicated at "B."

Passing completely around the upper portion of the body in parallel relation to band 5 is a second band 15 having an arcuate depression or groove 16 in which seats the bead 7. Thus it will be seen that the lid frame is free to rock upon the band 15 while knuckles 17 formed on the band 15 passing through the openings 8 and 9 allow the rib 7 to be disengaged from the groove 16 when the lid is in a predetermined position, with a result that the lid may be lifted off and placed behind the body of the casket when the body is being viewed. It will also be noted that the bead 7 extends approximately the length of the frame and 80 engages the entire corresponding surface of the groove 16 which extends approximately the length of the casket with a result that the strain when lifting the lid is taken up by practically the entire length of the casket. 85

A very important feature that I wish to call attention to at this point is the manner in which the bead 7 co-operates with the knuckles 17 as clearly shown in Fig. 5 which allows the frame 5 and with it the lid, to 95 have slight vertical play with the result that the entire weight of the lid may be brought into play for effectively forcing the tongue 3 into its associated groove thus assuring an air-tight connection between the 100 105 110

lid and body when a cement material is arranged in the groove.

Engaging the body of the casket is a carrying frame 18 which may be of the construction illustrated in my co-pending application, Serial Number 190,838; filed September 11, 1917, with an advantage that the frame may be detached from the body. In Fig. 6 I have shown the carrying frame 18 connected to a band 19 corresponding to the band 15 and having a groove 20 formed therein, and knuckles 21 for making a proper connection with the lid frame.

It is to be understood that the structural embodiment of the invention as a whole and its various features as shown are merely illustrative and not restrictive, since I am well aware that many of the details of the construction can be widely varied without departing from the spirit of the invention, I therefore do not desire to be limited in these particulars or in any other, except as set forth in the appended claims.

Having described my invention what I claim is:

1. A hinge connection for caskets, comprising a band connection to the body of the casket and having a groove extending approximately the length of the band; a frame connected to the lid of the casket and having a continuous rib seated in said groove

and knuckles extending from the body band and detachably engaging around the rib on said lid frame in a manner to allow slight vertical play of said lid.

2. A glass casket comprising in combination a body, a lid therefor, a frame for the lid including a longitudinal band having a rib extending substantially the length of the frame and a frame for the body having a groove extending the length of the frame and receiving said rib and knuckles extending from the body frame and passing through openings in the lid frame in a manner to provide a detachable engagement with the latter.

3. Means for connecting the lid of a casket to the body thereof including a band and extending around the body and having a groove extending approximately the length of the casket, a frame engaging said lid and having a rib therein against the entire surface of said groove and formed with openings at a point above said rib and knuckles formed on said body band and extending through said openings and detachably engaging said rib, the thickness of said knuckles being less than the height of said openings to allow slight vertical play of said lid for the purpose set forth.

In testimony whereof I affix my signature
GEORGE H. MELLON.
